(57) **CLAIM**

The ornamental design for a self-punching bone anchor inserter, as shown and described.

DESCRIPTION

FIG. 1 is a front perspective view of the self-punching bone anchor inserter;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in FIGS. 1-7 illustrate portions of the self-punching bone anchor inserter that form no part of the claimed design. The dot-dash lines illustrate boundary lines and form no part of the claimed design. The broken line break lines indicate a symbolic break in length. The appearance of any portion of the article between the broken line break lines forms no part of the claimed design.
